(57) **CLAIM**

The ornamental design for a mirror, as shown and described.

DESCRIPTION

FIG. 1 is a perspective view of a mirror showing my design; FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of another state of the mirror thereof; and,

FIG. 9 is a perspective view of further another state of the mirror thereof.

The broken lines shown in the drawings depict portions of the mirror in which the design is embodied that form no part of the claimed design.
